Primary Examiner — Calvin E Vansant*Assistant Examiner* — Mark T. Philipps(74) *Attorney, Agent, or Firm* — Scale LLP(57) **CLAIM**

The ornamental design for an intercooler, as shown and described.

DESCRIPTION

FIG. 1 is a front right perspective view of the intercooler.

FIG. 2 is a front left perspective view of the intercooler.

FIG. 3 is a back right perspective view of the intercooler.

FIG. 4 is a back left perspective view of the intercooler.

FIG. 5 is a front view of the intercooler.

FIG. 6 is a back view of the intercooler.

FIG. 7 is a left view of the intercooler.

FIG. 8 is a right view of the intercooler.

FIG. 9 is a top view of the intercooler; and,

FIG. 10 is a bottom view of the intercooler.

The broken lines depict portions of the intercooler that form no part of the claim.

1 Claim, 7 Drawing Sheets(56)
